INFANT'S SLEEPING GARMENT

Evelyn E. Wilson, Brookline, Pa.

Application May 13, 1941, Serial No. 393,283

8 Claims.

(Cl. 2—114)

This invention relates to sleeping garments for infants adapted for use as a garment per se but preferably in connection with a bed sheet or coverlet cooperating therewith. No entirely satisfactory sleeping garment has heretofore been devised for infants' use. By reason of the natural restlessness of the child, while sleeping, the garments and bed covers become disarranged and the child is unduly exposed, or the child is made uncomfortable through the entanglements of the garments as well as the bed clothing resulting from its various movements. Certain of the garments heretofore available unduly restrict the movements of the child with resultant discomfort to the child.

The principal object of the present invention is to provide a garment to be worn by infants while sleeping which will afford the utmost degree of protection and comfort to the infant, notwithstanding the natural restlessness of the infant.

A further object of the invention is to provide a sleeping garment for infants which will not only be efficient for its intended purpose but which may be inexpensively made.

A further object of the invention is to provide a sleeping garment for infants, and a coverlet to be used in connection therewith, which are so constructed and arranged that the infant may be readily and easily clothed with the garment with a minimum of trouble.

The nature and characteristic features of the invention will be more readily understood from the following description taken in connection with the accompanying drawings forming part hereof in which:

Figure 1 is a front elevation of an infant's sleeping garment embodying the main features of the present invention;

Fig. 2 is a top plan view on a reduced scale of the sleeping garment shown in operative relationship with a coverlet;

Fig. 3 is a detail view, enlarged, illustrating the construction and arrangement at the lower corner of the garment and coverlet;

Fig. 4 is a detail perspective view partly in section, illustrating more fully the cooperative relationship of the lower parts of the garment and coverlet; and

Fig. 5 is a detailed view looking from the under side of the corner of the garment and the coverlet in the stage of being assembled with respect to each other.

It will of course be understood that the description and drawings herein are illustrative merely and that various changes and modifica-

tions may be made in the structure disclosed without departing from the spirit of the invention.

Referring now more particularly to Fig. 1 of the drawings, the garment proper comprises an upper waist portion or section 10 and a lower skirt portion or section 11. The waist portion 10 comprises a back panel 12, and front sections 13 connected to the back panel at the shoulders 14 on each side of the neck opening 15 and at the sides below the arm openings 16. The front sections 13 may be gathered as at 17 to provide for shaping of the waist portion at the shoulders 14.

The skirt portion 11 of the garment is relatively loose for reasons hereinafter referred to and is preferably made substantially tubular and open at its lower end. The edges of the lower end of the skirt portion 11 of the garment are preferably reinforced by means of tapes 18, which tapes may be continued, as at 19, beyond the sides of the garment to provide extensions or attaching ties adapted to be used for a purpose and in a manner to be presently described. If desired, the ties may be detachably secured to the lower edge portions of the skirt section 11 by employing loops through which the ties 19 are disposed and from which the ties 19 extend.

The skirt portion 11 of the garment is connected to the waist portion 10 at the front and at the rear by relatively narrow portions 20 and 21. The connection between the skirt portion 11 and the waist portion 10 of the garment is preferably an integral one, although it should be understood that, if desired, these parts of the garment may be joined to each other by separable fasteners of any preferred type.

The narrow connection between the waist and skirt portions is effected by providing inwardly extending and oppositely located darts or other forms of cutout 22. The boundary edges of the cutouts 22 may be provided with elastic insertion disposed between a double row of stitching 23, serving to draw in the upper part of the skirt portion 11 which otherwise would extend to 24 as indicated in dotted lines in Fig. 1 of the drawings. Likewise the lower front edge 25 of the waist portion 10 at the cutout is similarly provided with elastic insertion along the edge of the cutout 22 of the lower part of the front sections 13 of the waist portion 10. The rear panel 12 along the lower edge provided at the cutout 22, is preferably left without the elastic insertion.

A vertical slit 30 is provided at the front of the waist portion 10 and is preferably extended downwardly a considerable distance into the

front of the skirt portion 11. This slit 30 is normally closed by any suitable fastening means but preferably a sliding separable fastener 31 of the Talon or Zipper type is employed for this purpose. If desired the slit 30 may be continued downwardly to the bottom of the skirt portion 11.

The coverlet 35 which is adapted to be used in connection with the garment is shown in Figs. 2, 3, 4 and 5 of the drawings, and may be made of blanket material, or if desired may be made of the same material as the garment proper. The coverlet preferably consists of a rectangular body portion having an upper edge 36, side edges 37 and a lower marginal edge portion 38. The lower marginal edge portion 38 is adapted to be turned or folded upwardly to a position to lie under the adjacent portion of the main body portion and enclose the lower edge of the skirt portion 11.

The body portion of the coverlet 35 is provided, near each side edge 37, with openings 40, suitably reinforced, and spaced so that the extensions or attaching ties 19 may be inserted therethrough.

The body portion of the coverlet 35 also has a pair of tapes 41 to provide attaching ties secured to the under side thereof, either by directly attaching the tapes to the body portion or by passing the tapes through loops 42 which are attached to the under side of the body portion 35. The body portion 35 is also provided near each edge 37 with openings 43, suitably reinforced and spaced, and preferably in longitudinal alignment with the openings 40 and the places of attachment of the tapes 41, so that upon folding of the marginal edge portion 38 the tapes 41 may be inserted through the openings 43.

The body portion of the coverlet 35 also is preferably provided on the upper face with upper tie tapes 44. The upper tie tapes 44 are preferably disposed at the upper edge 36 and spaced inwardly from the side edges 37 of the body portion 35 and are secured to the body portion 35 either by direct attachment thereto or by passing the tapes through loops 45 which are attached to the upper face of the body portion 35.

The spacing of the places of attachment of the tapes 41 and 44, and of the openings 40 and 43, inwardly from the side edges of the body portion of the coverlet 35, provides side marginal portions 46 for purposes hereinafter explained.

The manner of use of the garment of the present invention will now be explained although it will be understood that adherence to the sequence hereinafter set forth is not essential.

The front portion of the garment is opened by manipulation of the sliding fastener 31 and the child is placed in position with respect to the neck opening 15 and with its arms extending through the arm openings 16. The front of the garment is then closed by manipulation of the fastener 31.

The garment may if desired be used in this condition by securing the attaching ties 19 to the lower portion of the child's crib at each side thereof. The upward movement of the child will then be restrained by contact with the shoulder portions 14 of the waist portion 10 of the garment but nevertheless great freedom of movement of the child will be permitted. The arms of the child will not be restrained, the legs may be readily moved by reason of the fullness provided in the skirt portion 11, and the skirt portion 11 will also permit the child to turn during sleeping on either side or to sleep on its abdomen.

It is preferable, however, to use the coverlet 35 with the garment proper. For this purpose the

attaching ties 19 at the lower edge of the skirt portion 11 are inserted through the openings 40 in the coverlet 35 (see Fig. 5) to aid in holding the garment proper in position with respect to

5 the coverlet 35 and the lower marginal edge portion 38 of the coverlet is folded under, as indicated in Figs. 2, 3 and 4 and the ties 41 are passed through the openings 43. The two sets of lower ties 19 and 41 on each side may then be secured to the child's crib so that the garment proper and the coverlet 35 are firmly anchored at the lower portions thereof.

10 The upper sets of attaching ties 44 on each side may then be secured to the child's crib so that the coverlet is held in position at the upper edge thereof. The side marginal edge portions 46 may then be disposed as desired, such as by tucking under the other covers on the crib. The movements of the child, for sleeping in various 15 positions as heretofore pointed out, will still be relatively free, but the permitted movements of the child will not allow or cause it to become uncovered.

20 Additional covers may be disposed above or below the coverlet, as desired, and in accordance with the weather conditions.

I claim:

1. An infant's sleeping garment comprising connected waist and skirt sections, connecting 30 members carried by the lower portion of said skirt section, and a removable coverlet section for covering said skirt section, said coverlet section having a lower marginal edge portion adapted to be folded with respect to the lower portion of the coverlet section for enclosing the lower edge of said skirt section, said coverlet section having portions for receiving said connecting members of said skirt section and for holding the lower portions of said coverlet section and said skirt 35 section in engagement, and attaching ties at the lower portion of said coverlet section for holding the lower portion of said coverlet section in position.

2. An infant's sleeping garment comprising

45 connected waist and skirt sections, connecting members carried by the lower portion of said skirt section, and a removable coverlet section extending upwardly at least as far as said waist section, attaching ties carried by the upper portion of said

50 coverlet section for holding said portion in position with respect to said skirt section, said coverlet section having a lower marginal edge portion adapted to be folded with respect to the lower portion of the coverlet section for enclosing the lower edge of said skirt section, said coverlet section having portions for receiving said connecting members of said skirt section, whereby

55 said coverlet is retained in enclosing relationship with respect to the lower edge of the skirt section, and attaching ties at the lower portion of said coverlet section for holding the lower portion of said coverlet section in position.

3. An infant's sleeping garment comprising connected waist and skirt sections, connecting 60 members carried by the lower portion of said skirt section, and a removable coverlet section extending upwardly to said waist section, attaching ties for holding the upper portion of said coverlet section in position, said coverlet section having a lower marginal edge portion adapted to be folded with respect to the lower portion of the coverlet section for enclosing the lower edge of said skirt section, said coverlet section having

65 openings through which said skirt section connecting members are extended, and said lower

70 coverlet section having openings through which said skirt section connecting members are extended, and said lower

marginal edge portion having attaching ties secured thereto and openings in the lower portion of the coverlet section through which said latter ties are extended.

4. An infant's sleeping garment comprising an upper waist section having neck and arm openings and having a back panel portion and a front panel portion, said panel portions being connected across the shoulders and below the arm openings, and a lower generally tubular skirt section, said sections being separated by slits bounded by lower terminal edges of the waist section and upper terminal edges of the skirt section and being connected at the front and rear by centrally disposed portions, and members disposed along said upper terminal edges of the skirt section and along lower terminal edge portions of the waist section for contracting said edge portions.

5. An infant's sleeping garment comprising an upper waist section having neck and arm openings and having a back panel portion and a front panel portion, said panel portions being connected across the shoulders and below the arm openings, and a lower generally tubular skirt section connected to the waist section at the front and rear and separated at the sides by slits bounded by extensible lower terminal edges of the waist section and extensible upper terminal edges of the skirt section, the upper terminal edge of the skirt section being wider than the lower terminal edge of the waist section and members disposed along the upper terminal edges of the skirt section and along the lower front terminal edge of the waist section for contracting said edge portions.

6. An infant's sleeping garment comprising an upper waist section having neck and arm openings and having a back panel portion and a front panel portion, said panel portions being connected across the shoulders and below the arm openings, and a lower generally tubular skirt section, said sections being separated by side slits bounded by extensible lower terminal edges of the waist section and upper terminal edges of the skirt section and being connected at the front and rear by centrally disposed portions, members disposed along the upper terminal edges of the skirt section and along the lower front terminal edge of the waist section for contracting said edge portions, a longitudinal slit in one of said centrally disposed portions extending from the neck open-

ing towards the lower extremity of the skirt section, and closure means for said slit.

7. An infant's sleeping garment comprising an upper waist section and a lower skirt section, connecting portions extending between said sections to permit free turning movement of the waist section with respect to the lower portion of the skirt section, and a removable coverlet section extending upwardly to said waist section, attaching members for holding the upper portion of said coverlet section in relatively flat position independent of the movement of the waist section, the lower ends of said coverlet section and said skirt section having portions for folded engagement for closing the lower edge of said skirt section, attaching tie members connected to the lower portion of said skirt section, said coverlet section having openings through which said tie members are extended, and one of said sections having additional attaching ties secured thereto and extending through openings in the other section for securing the lower portion of said coverlet section in position.

8. An infant's sleeping garment comprising an upper waist section and a skirt section, connecting portions between said sections to permit free turning movement of the waist section with respect to the lower portion of the skirt section, and a removable coverlet section extending upwardly and overlapping said waist section, attaching ties secured to the upper portion of said coverlet section for securing the upper portion of said coverlet section in relatively flat position independent of the movement of the waist section, said coverlet section having a lower marginal edge portion adapted to be folded under the adjoining lower portion of the coverlet section for enclosing the lower edge of said skirt section, said coverlet section having openings through which said skirt section attaching ties are extended for securing the lower portion of said skirt section in position, said marginal edge portion having attaching ties secured thereto and openings in the lower portion of the coverlet section disposed above said first mentioned openings through which said latter attaching ties are extended for securing the lower portions of said coverlet section in relatively flat position.
